CLAIM

The ornamental design for a container for an air freshener, as shown and described.

DESCRIPTION

FIG. 1 is a front elevational view of a container for an air freshener, showing my new design;

FIG. 2 is a rear elevational view thereof;

FIG. 3 is a side elevational view thereof, the opposite side being a mirror image of that shown;

FIG. 4 is a top plan view thereof; and,

FIG. 5 is a bottom plan view thereof.

FIG.1
